UNITED STATES PATENT OFFICE.

AUGUST H. PAPE, OF KENTFIELD, CALIFORNIA, ASSIGNOR OF ONE-HALF TO WILLIAM B. LARKINS, OF SAN FRANCISCO, CALIFORNIA.

WINDOW FASTENER.

Application filed November 11, 1919. Serial No. 337,310.

To all whom it may concern:

Be it known that I, AUGUST H. PAPE, a citizen of the United States, residing at Kentfield, in the county of Marin and State 5 of California, have invented new and useful Improvements in Window Fasteners, of which the following is a specification.

The present invention relates to improvements in windows, the object of the invention being to provide a window which can readily be closed or opened to any extent desired, and which will also be prevented from rattling in the position in which it is left after operation thereof.

Fig. 1 is an enlarged vertical section of a portion of a window frame showing the horizontally movable glass clamping channel member in full line released position and in dotted line clamping position; Fig. 2 is a view similar to Fig. 1 showing the longitudinally slidable channel member in full line lower position and in dotted line raised or upper position; Fig. 3 is an elevation of the parts shown in Fig. 1 looking 15 from the inner side of the window frame; Fig. 4 is a rear elevation of the operating channel member, the vertically slidable channel member being shown in its upper position; Fig. 5 is a side view, partly in section, 20 showing the means for effecting vertical movements of the vertically movable channel member; Fig. 6 is an enlarged vertical section of a portion of a modified arrangement; Fig. 7 is an enlarged broken trans- 25 verse section of the structure shown in Fig. 6; Fig. 8 is a front elevation partly in section of the modified structure of Fig. 6.

Referring to the drawing, in which my improved window is shown, 2 indicates the 30 window frame, the vertical sides 3 and 4 of which are grooved, the grooved side 3 having therein a channel iron 6 extending for the greater part of the height of the window and enveloped by a sheet 7 of cloth or felted 35 material closely surrounding it and adapted to receive the adjacent edge of a sheet 8 of glass, the vertical sides of which can slide vertically in the grooved sides of the window frame, said sheet 8 of glass being raised 40 vertically by well known means, such as a strap attached to the lower portion of said sheet, or a sprocket gear and chain, the latter of which may be attached to the bottom of the sheet. The other grooved side 4 of 45 the window frame contains closely fitting

therein a metal channel iron 11 which is vertically slidable in said grooved side and within the channel iron 11 is a channel iron 12 covered with cloth or felt 13 and which receives the other vertical edge of the sheet 8 of glass and which does not move vertically but is capable of moving horizontally within the channel iron 11 to and from the adjacent edge of the sheet of glass. Said channel iron 12 is prevented from moving vertically while permitted to move horizontally by its being riveted, as shown at 14, 50 to the lower portion of a spring tongue 17 through a hole in the upper portion of which extends a screw 18 screwed into the 55 window frame.

To permit the channel iron 11 to move vertically in the groove 4 and at the same time to permit the spring tongue 17 to be secured by a screw to the window frame, the 60 channel iron 11 is formed with a central vertical slot 19 sufficiently large to receive the screw 18 while the channel iron 11 is in different positions. This slot 19 is of greater 65 width at its lower than at its upper portion and is made sufficiently wide to receive the lower end of the tongue 17 therein and the upward motion of the channel iron 11 is 70 regulated by the bottom of the slot striking against the bottom of said tongue. Said 75 channel iron 11 is moved up or down by means of a handle 21 of a lever 22 fulcrumed, as shown at 23, upon one side of the channel iron 11, a free end of the lever being received in a hole 24 cut in the window 80 frame. Upon raising the handle the free end of the lever presses against the bottom of said hole and raises the channel iron 11, and upon depressing the handle, a contrary 85 motion of the channel iron 11 takes place.

A spring plate 26 of the same width as the spring tongue is interposed between said spring tongue and the channel iron 11 and has a hole through which the screw 18 90 extends snugly and the pressing of said spring plate upon the channel iron 11 tends to hold up the channel iron 11 against its own weight. The lowering or raising of the channel iron 11 is used to move inwardly or outwardly the channel iron 12 95 and thus to compress or release the sheet 8 of glass between the two channel irons 12 and 6 by the following mechanism. On the outer side of the channel iron 12 are secured by screws 29 upwardly tapering wedges 31 100

105

110

and the channel iron 11 is formed with upper and lower holes 32 to permit the upper and lower wedges to pass therethrough and be received within upper and lower recesses 33 in the window frame. When the channel iron 11 is raised by raising the handle 21, the wedges 31 can pass through the holes 32 in the channel iron 11 and into the recesses 33 in the window frame and the glass sheet 8 is no longer held tightly between the channel irons 12 and 6 and can be raised or lowered as desired by any mechanism suitable for the purpose, but when the sheet 8 has been raised or lowered to the desired position, then the channel iron 11 is depressed by depressing the handle 21, whereupon the channel iron 11 engages the thin parts of the wedges 31 and presses said wedges out of the recesses 33, thus pressing the channel iron 12 against the adjacent vertical edge of the glass sheet 8 and thus clamping said glass sheet between said channel irons 12 and 6. The upper ends of the holes 32 are formed with receding lips 35 to engage the wedges 31. The spring 17 normally tends to retract the channel 12 into the channel 11.

In the form of the invention shown in Figures 6, 7, and 8, the metal channel iron 12' has secured on its outer side upper and lower racks 34 which engage pinions 36 pivoted upon shafts 38 extending through sides of the metallic channel 11'. The channel 12' can be moved up or down by a button 41 connected with the lower end of the lower rack 34 by a neck 42 in any desired manner. As said metal channel 12' is moved longitudinally, the racks attached thereto turn said pinions 36, being always maintained in engagement with said pinions by flat springs 44 secured at their lower ends to said racks and extending upwards therefrom and outside pins 46 driven through the metal channel iron 11' of the window frame, their upper ends abutting the middle portion of said metal channel 11', the resiliency of said springs forcing the racks outwards and into contact with said pinions. The downward movement of said racks caused by the downward pressure on said button 41 has the effect of moving the

metal channel 12' inwardly clamping the sheet of glass between the fixed and movable metal channels 6 and 12', because the shafts on which the pinions rotate are located eccentrically thereto, and the downward movement of the racks causes the wide sides of the pinions to be innermost, thereby pressing the racks inwardly, and pressing the cloth covered channel 12' inwardly against the edge of the sheet of glass, clamping said sheet between the channels 6 and 12', so that it is no longer able to vibrate and is held firmly in position. Consequently, should it be desired to raise the sheet 8 of glass, this is permitted by moving the button 41 upwardly, raising the movable channel iron 12', causing the pinions to rotate so that the narrow sides thereof are between the shafts and the racks, so that the movable channel 12' can move outwardly, which it immediately does, due to the tension of the springs 44, leaving the sheet of glass loose between the channels 6 and 12' and permitting it to move vertically into any position.

I claim:

1. In a window structure, the combination with a window frame and a window slideable in grooves therein; of a pair of channel members between the window and frame receivable one within the other, and means whereby vertical movement of one of the members imparts relative horizontal movement to the members to force one of the same into clamping relation with the window.

2. Means for clamping a sheet of glass slideable in grooves of a window frame, comprising a channel iron movable in one of said grooves and surrounding one of the edges of the sheet, a plurality of wedges on the back of said channel iron, a vertically movable channel iron surrounding the first-named channel iron and having holes through which said wedges can pass, and portions adjacent to said holes normally engaging said wedges, the window frame being recessed to receive said wedges, and means for moving vertically said second channel iron.

AUGUST H. PAPE.
